DUPLICATING MACHINE

John R. Nalbach, Oak Park, Ill.

Application December 24, 1937, Serial No. 181,481

10 Claims. (Cl. 101—133)

This invention relates to improvements in duplicating machines.

One object of the invention is to provide a duplicating machine of the flat bed type which is of economical construction and is provided with a manually operable carriage arranged to lay copy sheets upon a hectograph surface during movement of the carriage in one direction, and which strips the paper from the surface upon the return movement of the carriage.

Another object of the invention is to provide guide means for the carriage which is so mounted as to enable a platen roller carried by the carriage to be rolled over the copy sheets to press the same into uniform contact with a hectographic surface whether said surface lies precisely in a particular plane or whether different hectograph members such as gelatin films, pads, pan-contained, or other suitably supported hectographic masses or ink pads have their duplicating or transferring surfaces disposed in a given plane.

In preparing hectographic masses of gelatin composition for duplicating machines, it is not always possible to procure uniformity in thickness, and hence where a guided platen roller of a flat bed type machine is employed for pressing copy sheets against the hectographic surface, provisions generally are made to compensate for variations of thickness of the hectographic material either by so mounting the platen roller in the carriage as to afford relative vertical movement of the roller with respect to the guided carriage, or by enabling the bed to be adjusted with respect to the roller.

With the present improvements, the pressure of the copy sheets into proper contact with the hectographic surface is provided for by mounting the guide members for the carriage for free pivotal movement as may be determined by the rolling action of the platen along the surface of the hectographic material. It will therefore be seen that with the present machine, variations in thickness of the hectographic material does not preclude the making of uniformly clear copies.

The present construction is of advantage also in that the entire carriage can be moved out of the way when a new hectographic member is to be installed in the machine.

Another object of the invention is to provide a supporting frame or bed for the hectographic material supporting members by means of which such members can readily be placed in position or removed for replacement by another member.

Another object of the invention is to provide a duplicating machine of the flat bed type adapted

to accommodate conventional duplicating pads of the form employed, for example, in rotary duplicating machines, means being provided for tensioning the pads upon the bed.

Other advantages of the present invention relate to various features of construction and arrangement of parts which will be apparent from a consideration of the following specification and accompanying drawings, wherein:

Fig. 1 is a top plan view of a flat bed duplicating machine embodying the present improvements;

Fig. 2 is a side elevation of the machine shown in Fig. 1;

Fig. 3 is an end elevation thereof;

Fig. 4 is a sectional view taken on the line 4—4 of Fig. 1;

Fig. 5 is a sectional view taken on the line 5—5 of Fig. 1;

Fig. 6 is a longitudinal sectional view taken on line 6—6 of Fig. 1 and showing in dotted lines the carriage and a carriage guide swung to a position above the bed of the machine;

Fig. 7 is a broken sectional elevation similar to that shown in Fig. 6 illustrating the carriage moved forwardly from the position shown in Fig. 6;

Fig. 8 is a longitudinal sectional view taken on line 8—8 of Fig. 9, illustrating a modified form of duplicator adapted for using a gelatin pad as distinguished from a pan-contained hectographic mass;

Fig. 9 is a transverse section taken on line 9—9 of Fig. 8; and

Fig. 10 is an enlarged broken detail view illustrating the band tensioning mechanism shown in Fig. 8.

In Figs. 1 to 7 of the drawings, 10 indicates generally the base or bed of the machine which is frame-like in shape. The bed shown in the drawings comprises a pair of angular-shaped longitudinal members 11, the vertical sides 12 of which define the longitudinal side walls of the machine, and the horizontal portions 13 of which provide a support for the hectographic members, 45 as will be described hereinafter.

Adjacent the forward ends of the side members 11 the same are connected together by an angular-shaped transverse member 14 and the rear ends of the side members 11 are connected by a similarly shaped transverse member 15. The members 14 and 15 may be of sheet metal also and secured to the side members 11 by welding or any other approved means. This construction provides a frame-like bed, as will be seen,

Second to flanges 13 of the side frame members 11 are longitudinal stiffening and spacing strips 16 which are of a width less than the width of the flanges 13, thus providing ledges 17 along the inner longitudinal sides of the rectangular-shaped opening of the frame-like construction for supporting the hectograph or duplicating member which, as shown in Figs. 1 to 7, inclusive, is in the form of a sheet metal pan 18 provided with flanges 18a directed longitudinally from the end walls 18b thereof. The hectographic material, such as a conventional gelatin-glue composition material 19 is carried in the pan. The pan is of a size to fit within the frame-like opening of the base and is supported at its longitudinal edges by ledges 17.

Pivottally secured to the forward end of the base is a carriage guide comprising a pair of parallel rods 20 which, at the rear ends, are connected by a transverse member 21 and at the forward ends are secured to a transverse rod or pivoting member 22 which has ends disposed in recesses provided in the side flanges 12 of the base, as shown clearly in Fig. 1. As will be noted in Fig. 5, for example, the pivotal axis of the carriage guide is disposed above the plane of the surface of the hectograph material 19, the level of which may vary somewhat, depending upon the amount of the molten material poured into the pan 18. The guide thus is movable about its pivot toward or away from the hectographic material, and as a matter of fact, may be swung forwardly about its pivot beyond 90° if desired, so as to be out of the way when a hectographic supporting member, such as a pan 18, is to be removed or replaced within the machine.

Slidably positioned on the rods 20 is the carriage comprising platen journals 23 within which is journaled a rotatable platen roller 24. Secured to the member 23 also is a transverse sheet metal member 25 which serves as a handle in operating the carriage longitudinally of the machine. Forwardly of the roller 24 a plate 26 is attached to the journal members 23, which member constitutes a combined sheet guide and stripping member. The member 26 may be of sheet metal secured at its ends to the members 23 by means of screws 27, or the like, and, as will be seen in Figs. 6 and 7, is inclined rearwardly, having its lower end disposed a short distance above the surface of the hectographic mass 19.

In using the machine, the master sheet bearing the copyable material to be duplicated is slid rearwardly along the upper surface of the member 26 until it contacts the rear vertical end wall 18b of the pan 18 which, as shown, projects a slight distance above the level of the hectographic mass 19. The projecting end wall 18b thus forms a stop or, in effect, a margin bar for the master as well as for the subsequent copy sheets. At the time the master is inserted, the carriage is retracted to its rearmost position, so that the platen roller 24 rests upon the flange 18a of the end wall 18b at the rear of the machine as shown in Fig. 6. With the sheet 28 in the position shown in said figure as above described, the carriage is pressed forwardly manually by means of the handle 25. The platen roller 24 presses the sheet 28 into contact with the surface of the hectographic material and as the carriage is advanced, rolls the sheet into smooth contact with such material. The operator can press the carriage forwardly with one hand and retain hold of the other end of the

sheet with the other hand if he desires, such end preferably being the top end of the sheet inasmuch as generally no matter will be transferred to such end.

After leaving the sheet on the duplicating surface for a short time, the carriage is pulled back to original position, that is, to a position upon the support 18a, the operator retaining hold of the top end of the sheet and exerting tension thereon. It will be seen that during the return movement, the lower edge of the plate 26 will lift the sheet from the somewhat tacky surface of the gelatin mass.

After the copy has thus been transferred to the duplicating mass, the copy sheets may be run through the machine to make the required number of copies. The copy sheets are inserted one at a time in the machine as shown in Fig. 6, the carriage then pressed forward from the supporting and elevating flange 18a as above described and as illustrated in Fig. 7, the operator retaining hold of the upper end of the sheet until the sheet has been rolled over the matter to be duplicated. The carriage is then pulled rearwardly to the position shown in Fig. 6, during which rearward movement, the plate 26 strips the copy sheet from the duplicating surface.

It will be noted that the pivotal mounting of the guide including the guide rods 20 enables the carriage to move freely to or from the plane of the duplicating surface. If such surfaces vary in elevation as between different duplicating masses, uniform prints will still be made due to the fact that the roller can descend to press the sheets into proper contact therewith. Thus no provision need be made in this machine for adjusting the hectographic support into a predetermined plane, as is the case with the machines where the guides are fixed; nor need the platen roller 24 be made relatively movable within its carriage.

As shown in the drawings, the frame 10 is provided with legs 30 to space the same above the top of the desk or table upon which the machine is used. These legs preferably are of suction-cup construction to prevent the machine from sliding during use.

The pan 18 preferably is provided with a sheet metal cover 31 which during use of the machine may be placed under the pan (see Figs. 5 and 6) or it may be placed in the inclined position shown by dotted lines in Fig. 6 wherein it is supported by the transverse pivot rod 22 and the end 14 of the bed and constitutes a support for a supply of copy sheets which are conveniently accessible during use of the machine.

The form of the device shown in Figs. 8 to 10, inclusive, is generally similar to that above described except that it is modified for utilizing duplicating bands or pads as the hectograph surface rather than a pan-contained gelatin mass. The machine comprises side frame members 32 which may be integral with a bottom 32a which supports a pad 33 comprising a fabric 65 backing 34 and a hectographic coating 35. These pads may be of the type generally used in rotary duplicators, for example, and are provided with suitable clips 36 at the ends thereof for attachment to means which hold the pads 70 in position. The clips 36 illustrated are of sheet metal and engage the ends of the backing strips 34, the clips having a plurality of openings 37 therein for receiving suitable attaching means. The clips illustrated herein are of the

form shown more in detail in the Whitehead Patent No. 2,094,628 granted October 5, 1937.

To the rear end of the bottom 32 of the machine is attached a combined platen rest and margin bar 38 which is formed of sheet metal and is provided with horizontal flanges or fingers 38a on which the platen 24 of the machine rests when the machine is not in use or during intervals when paper is being fed into the machine, as shown in Fig. 8. The fingers 38a are adapted to pass through apertures 37 for anchoring one end of the pad on the bed. The opposite end of the pad is provided with a similar clip through openings 37 in which extend fingers 39 of a tensioning device indicated generally by the numeral 40. The device 40 comprises a transverse member 41 with which the fingers 39 are integral and a transverse adjustable member 42, the ends of which are slidably in suitable guides 43 attached to the bottom of the machine adjacent the lateral edges thereof as shown in Fig. 9. The members 41 and 42 are welded or otherwise rigidly attached together or made integral, as desired.

The member 42 has a central downwardly directed flange or lug 44 through an opening in which extends a tensioning screw 45 carrying a nut 46 mounted in a retainer clip 47 which is attached to the base 32. The screw 45 is provided with a collar 48 disposed at the rear of the flange 44. Turning the screw in one direction or the other will move the member 41 and finger 39 in one direction or the other longitudinally of the machine for applying tension to the pad and drawing the same tautly upon the base 32.

The modified machine, insofar as the platen journals 23, platen roller 24, guide rods 20 and sheet laying and stripping plate 26 are concerned is similar to the form of the invention above described. The modified machine of Figs. 8 to 10, inclusive, is particularly adapted for use with the described pads or bands rather than pan-contained masses, as mentioned.

The hectographic masses or pads above referred to are generally of gelatin-glue composition and retain ink from an applied master and transfer it to copy sheets as is well known. In referring to such masses, however, as hectograph members, such term is used generically and is not to be construed as limited to gelatin-glue composition material since the master may comprise a stencil sheet imposed upon an ink-pad supported by the bed of the machine for printing upon copy sheets impressed thereon by the mechanism described.

While I have shown and described certain embodiments of the improvements for the purpose of illustration, I do not wish to be restricted specifically thereto except as so limited by the appended claims.

I claim:

1. A flat bed duplicator comprising a supporting base, a hectographic member supported thereby, a pair of parallel platen guide rods disposed longitudinally of said base and pivotally attached at the forward ends thereof to said base and being freely movable about said pivot during duplicating operations to enable a platen roller to exert uniform pressure on the duplicating member during such operations, a pair of platen journals slidably carried by said guide members, and a platen roller carried by said journals and manually movable longitudinally of the base for pressing copy sheets into contact

with the surface of said hectographic member.

2. A duplicator comprising a supporting base, a hectographic member supported by said base, a pair of platen roller guide members extending longitudinally of said base and being pivotally attached thereto at the forward end thereof and being freely swingable about the pivotal axis during duplicating operations to enable a platen roller to exert uniform pressure on the duplicating member during such operations, a pair of platen journals slidably mounted on said guide members, a platen roller carried by said journals and adapted for rolling copy sheets into contact with said hectographic member, and a combined sheet guiding and stripping member carried by said journals forwardly of said roller.

3. A duplicating machine comprising a supporting base, a hectograph member thereon, a carriage comprising a platen roller arranged for rolling copy sheets into contact with said member, and a guide comprising a pair of parallel rods disposed laterally of said hectograph member for guiding said carriage longitudinally of said hectograph member and pivotally attached on a transverse axis to said base at the forward end thereof and being freely swingable about said pivotal axis for enabling said carriage to be moved as a unit toward and away from said hectograph member.

4. A duplicating machine comprising a supporting base providing a support for a hectographic member, a hectographic member thereon, a carriage guide comprising a pair of connected parallel rods disposed laterally of said hectographic member and pivotally secured on a transverse axis at one end to said base adjacent one end of the latter and arranged for free movement about the pivotal axis thereof during duplicating operations, and a carriage slidably mounted on said rods and comprising a platen roller arranged for rolling contact with said hectographic member and movable with said guide toward or away from said hectograph member.

5. A duplicating machine of the flat bed type comprising a base of rectangular frame-like form defining a recess for receiving a hectograph supporting member, a hectograph supporting member in said recess, a carriage movable longitudinally of said member and comprising a platen roller for pressing copy sheets against the hectographic surface of said member, a guide member comprising a pair of rods disposed laterally of said hectograph member for guiding said carriage during the longitudinal movements of said platen, said guide member being pivotally attached to said base adjacent the forward end thereof for swinging movement toward and away from said hectographic surface whereby said roller can be moved freely into position for pressing copy sheets into contact with said surface during longitudinal movement of the carriage, a combined sheet guide and stripper carried by said carriage, and means adjacent the rear of said supporting member and projecting above the same and constituting a margin bar for the copy sheets and an elevated rest for said roller during the insertion of copy sheets into the machine.

6. A flat bed duplicator comprising a base for supporting a duplicating member, a pair of parallel platen guide rods disposed longitudinally of said base and pivotally attached at the forward ends thereof to said base and being freely movable about said pivot during duplicating

operations, a pair of platen journals slidably carried by said guide members, and a platen roller carried by said journals and manually movable longitudinally of the base for pressing copy sheets into contact with the surface of said duplicating member.

- 5 7. A duplicator comprising a bed, clip engaging members at opposite ends thereof for engaging the clips of a duplicating band adapted to be attached upon said bed, one of said members comprising clip engaging fingers constituting a platen rest and a margin bar, said other member being adjustable longitudinally of said bed, means for adjusting said last mentioned member for tensioning a duplicating band upon said bed, and means for laying sheets on and stripping the same from said band comprising a guide rods pivotally attached to said bed, and a carriage movable longitudinally of said rods over said band comprising a platen roller and a co-operating sheet stripping plate.
- 10 8. A duplicating machine comprising a supporting base providing a support for a duplicating member, a duplicating member thereon, a platen roller movable over said member and provided with guide means pivotally mounted on said base on a transverse axis enabling the roller to be moved toward and from said member, and a platen roller rest at one end of said support for
- 15 20 25 30 supporting the roller out of contact with the

duplicating member and constituting a margin bar for copy sheets inserted in the machine.

9. A duplicating machine comprising a base for supporting a duplicating member, a pivotal guide structure attached to said base and comprising a platen roller slidable longitudinally thereof over a duplicating member on said base for pressing copy sheets thereon and movable with said structure into and from operative position with respect to said member, and a roller rest disposed at an elevation above the surface of the duplicating member at the end thereof remote from the pivotal axis of said structure for supporting the roller out of contact with said duplicating member and constituting a margin bar for copy sheets inserted in the member.

10. A duplicator comprising a bed for supporting a duplicating member, a platen roller arranged to press a copy sheet into contact with said duplicating member, journals for said roller, a guide structure on which said journals are slidably mounted and rectilinearly guided during duplicating operations, and pivot means adjacent one end of said bed for supporting said structure for free movement on a transverse axis during duplicating operations whereby said roller is free to press a copy sheet into uniform contact with the surface of said duplicating member.
